CLAIM

The ornamental design for a portable electrical energy storage device with components, as shown and described.

DESCRIPTION

FIG. 1 is a front perspective view of a portable electrical energy storage device with components showing our new design, a rear perspective view being a mirror image thereof. FIG. 2 is a perspective view of the bottom thereof. FIG. 3 is a bottom plan view thereof; and,

FIG. 4 an enlarged detail view of area 4 circumscribed within FIG. 2.

The dash-dash broken line immediately adjacent to the shaded areas in FIGS. 2-4 depicts the bounds of the claimed design and form no part thereof. The dash-dot-dot-dash broken line in FIG. 2 identifies the area of the detail shown in FIG. 4 and forms no part of the claimed design. All other broken lines depict environmental structure and form no part of the claimed design.
